UNITED STATES PATENT OFFICE.

SAMUEL P. BUSH AND GEORGE M. MURPHY, OF COLUMBUS, OHIO, ASSIGNORS TO THE BUCKEYE STEEL CASTINGS COMPANY, OF COLUMBUS, OHIO.

AUTOMATIC CAR COUPLER.

Application filed April 18, 1923, Serial No. 632,907. Renewed December 23, 1924.

To all whom it may concern:

Be it known that we, SAMUEL P. BUSH and GEORGE M. MURPHY, citizens of the United States, and residents of Columbus, 5 in the county of Franklin and State of Ohio, have invented certain new and useful Improvements in Automatic Car Couplers; and we do hereby declare the following to be a full, clear, and exact description of the 10 invention, such as will enable others skilled in the art to which it appertains to make and use the same.

Our present invention relates to automatic car couplers and has for its object to 15 provide a novel construction whereby the throw of the knuckle is accelerated, the knuckle may be fully opened with a decreased travel of the locking block, and a maximum bearing and support for the locking block is furnished. These stated objects 20 and other incidental objects which will appear in the course of the following description are attained in such a device as is illustrated in the accompanying drawings, 25 and the invention resides in certain features defined in the appended claims.

In the accompanying drawings, Figure 1 is a view in section through a draw head and knuckle, the locking block and lifting lever for the latter being in elevation; Figures 2, 3 and 4 are similar views showing the successive positions of the locking block and knuckle during the upward movement of the locking block; Figure 5 is a similar 30 view showing the knuckle in a partly open position and the locking block resting on the tail of the knuckle; Figures 6 and 7 are views of the knuckle; Figures 8, 9 and 10 are views of the locking block; Figure 11 is a view in perspective of the coupling, the guard arm side of the head being broken away, and Figure 12 is a view in section through the guard arm.

14 represents the draw head of the coupling provided with ears 15 having oppositely disposed lugs 16 which are integral with the ears 15 and head 14, the outer margin of the lugs being circular as shown in Figure 11.

50 The draw-head is provided intermediate the ears with the stops 17^a against which the shoulders 18^a on the knuckle abut when the latter is in closed position, thus assisting the other parts to be hereinafter referred to in

taking the buffing stresses. The knuckle 19 55 is recessed as at 20, on its upper and lower faces, to receive the lugs 16 on the ears of the draw-head, and the said recesses 20 are so located and of such shape that the wall 21 thereof bearing against the lugs 16, and 60 the shoulders 18^a bearing against the stops or abutments 17^a take, as before explained, the buffing stresses. The rear inner surface 18 of the wall 21 of the recess terminates in a position to take part of the pulling 65 stresses, thus relieving the pivot pin of much stress in pulling.

The ears 15 and lugs 16 are provided with a pin hole, and the knuckle 19 is provided with a corresponding hole for the passage 70 of the pin which locks the knuckle to the draw-head.

The knuckle 19 is provided with a tail 22, the upper and lower faces of which are inclined upwardly and rearwardly as shown 75 in Fig. 7. The upper face is provided at its outer edge with a rib 23 adapted to engage a shoulder or surface on the locking block for lifting and supporting the latter, while a similar rib 123 is provided on the lower 80 face for a purpose which will presently appear.

The locking block 24 which is shown detached in Figs. 8, 9 and 10, is provided with a depending leg 25, terminating in a toe 26, which projects horizontally, or at a slight inclination from the lower end of the leg. The underside of this leg, or the toe at the end of the leg, has an inclined surface as at 27, extending about half the length of the toe, and beyond this, the lower face of the toe is approximately horizontal. The locking block 24 is provided with a lateral shoulder or surface 28 adapted to be engaged by the rib 23 on the knuckle tail, and it is also provided at its upper end with a horizontally projecting lip 29 adapted to bear against the ribs 30 formed on the inner face of the side wall of the draw-head. The draw-head is provided in its throat at one 100 side with an inclined seat or shelf 31 extending in the direction of the length of the coupling and adapted to support the locking block in its lock set position. The ribs 30, it will be noted, have their upper portions 105 301 disposed parallel or approximately parallel with the top side wall of the draw-head while their lower portions 302 are

sharply beveled. When the locking block moves upwardly, the lip 29 rides upon the beveled portions of the ribs and a positive tilting action of the lock results.

5 Pivoted to a bracket 32 depending from the guard arm of the draw-head, is the lever 33, the rounded free end of which is adapted to engage the lower face of the toe 27 of the locking block 24, for lifting the same, 10 the lower end of the coupling head having an opening therein for the passage of the lever 33. This lever is connected with a pull-rod 34 which in turn will be connected with an actuating lever not shown.

15 Fig. 1 shows the locking block in its normal locking position; Figure 2 shows it slightly raised prior to going on lock set; Figure 3 shows it resting on the shoulder 31 or in set position; Figure 4 shows it in 20 its highest position with the knuckle thrown to open position and Figure 5 shows the knuckle partly closed with the locking block resting thereon.

25 In describing the action of the lock in going onto its seat, we will first describe the sliding action due to the inclination of the surface 27, as it can go onto its set in this way, and then refer to the action of the toe 26 in tilting the lock, the latter adding 30 to the positiveness of the operation.

When the knuckle is closed and locked, the locking block rests well down in the head, so that the portion of the block above shoulder 28 is in the plane of the tail of 35 the knuckle, while the shoulder 28 rests on the upper end of a bearing surface 310 formed on the inner side of the front wall of the draw-head in the corner formed by the same and the side wall. The locking 40 block is thus given the maximum support in its lowest position so that it will remain in operative relation to the knuckle and cannot become jammed or tilt into such a position that it must be laboriously dislodged before the knuckle may be operated. To release the knuckle, a pull is exerted on 45 rod 34 which actuates lever 33 in a direction to carry the free end of the latter into contact with the lower face of the extension 25 of the locking block. As the lever is moved, its free end engages and slides on the inclined surface 27 of the locking block thus tilting the locking block from the position 50 shown in Fig. 2 to that shown in Fig. 3, and in so doing the lower inclined surface 27 of the locking block slides on the end of the lever 33, thus bringing the lower edge of the extension 25 of the block in the plane of and over the lock seat 31. If 55 for any reason the block fails to slide into position over its lock seat 31, a continued upward movement of the lever 33 will carry the toe 26 of the extension 25 of the lock into engagement with the tail of the knuckle 60 and thus positively tilt the lock until the

lower edge of the extension is over the seat 31. By now releasing the lever 33, the locking block will settle down and rest on its seat 31. If the knuckle be now thrown to open position by any means other than the 70 lever 33, the rib 23 on the top of the knuckle tail will, during said opening movement, come in contact with the shoulder 28 on the locking block, at one side of the center of gravity of the latter, thus elevating the 75 block and causing it to tilt or swing away from the seat 31. This swinging or tilting movement is limited by the end of the toe 26 contacting with the surface 35 of the locking block housing. This surface 35 is 80 continued up at the rear in the form of a beveled or inclined extension 35^a, and at the extreme rear by the narrow strip or surface 35^b against which the toe bears and prevents any part or edge of the locking 85 block from moving over into the plane of the top edge of the surface 35. By now closing the knuckle, after the same has been wholly or partly opened, the lock continues to ride on the rib 23 and is gradually lowered until the knuckle swings clear of the locking block thus permitting the latter to drop into position shown in Fig. 1 and lock the knuckle in its closed position.

If it be desired to throw the knuckle to open position by means of the lever 33, a continued pull on rod 34 will elevate the locking block until the top surface of the toe 26 of the extension 25 of the locking block engages the inclined or cam face of the knuckle tail formed by the rib 123 and a continued movement will then forcibly move the locking block to its highest position and throw the knuckle to its open position. The continued upward movement of the locking block brings together the inclined faces of the rib 123 and the toe 26 so that the throw of the knuckle is very easily started and the movement of the knuckle to open position is accelerated. 105 During this movement the upper end of the locking block will tilt inwardly or toward the left, thus causing its lip 29 to engage and ride on the ribs 30, while the front and rear walls of the housing prevent any endwise vibratory movement of the block. When the lip 29 impinges upon the beveled portion 302, the locking block is 110 positively tilted to the right which action causes the lock to throw the knuckle open to the limit with a minimum travel of the lock.

115 It will be observed that the locking block is wholly inclosed within the housing and that provision is made for guiding both ends of the locking block in its upward and downward movements.

Again the lock seat being at one side of the housing and extending in the direction of the length of the draw-bar, the locking 120

block cannot be dislodged from its lock set position by impacts or blows incident to coupling.

The means for tilting the locking block 5 and moving it to its lock set position are simple and positive. When the knuckle is closed, the lock descends to its lowest position in locking the knuckle and is firmly supported by the walls of the housing and 10 the bearing surface 310, and with the lock in this position, the abutments under compressive stresses on the knuckle and draw-head co-act, as do the surfaces 19 of the knuckle and the surfaces of the lug 16 under pulling stresses, thus relieving the pivot pin, to a very large degree, from stresses.

While we prefer to actuate the locking block from below, as described, it may be provided, as shown in Fig. 9 with means 20 for its attachment to a lifting chain.

It is evident that many slight changes might be resorted to in the relative arrangement of parts shown and described without departing from the spirit and scope of our 25 invention, hence we would have it understood that we do not wish to confine ourselves to the exact construction and arrangement of parts shown and described, but,—

Having fully described our invention 30 what we claim as new and desire to secure by Letters Patent, is:—

1. In a car coupling, the combination of a draw-head having a lock set seat on an inner side wall and a bearing surface in the

lower portion of the corner bounded by 35 said side wall and the front wall, a knuckle, and a locking block having a lateral shoulder to rest upon the upper side of the bearing surface when the block is in its lowest 40 position, the block also having a terminal toe which when the block is lifted is caused to tilt away from the knuckle and over the seat and by its continued upward movement throws the knuckle to open position.

2. In a car coupling, the combination of 45 a draw-head having a lock set seat on an inner side wall and a bearing surface in the lower portion of the corner bounded by said side wall and the front wall, a knuckle, and a locking block having a lateral shoulder to rest upon the upper side of the bearing surface when the block is in its lowest 50 position, the block also having a terminal toe and when lifted from above it being so balanced that when the knuckle is cleared 55 the block tilts by gravity away from the knuckle and over the seat and by its continued upward movement the terminal toe engages the bottom of knuckle and throws the knuckle to open position.

In testimony whereof, we have signed this specification in the presence of two subscribing witnesses.

S. P. BUSH.
GEO. M. MURPHY.
